ATTORNEYS.

UNITED STATES PATENT OFFICE.

ANTON T. WEHNER, OF SAN FRANCISCO, CALIFORNIA.

PERMANENT-HAIR-WAVING APPARATUS.

Application filed July 30, 1927. Serial No. 209,495.

This invention relates to a new and improved heater used in the art of permanent hair waving.

An object of this invention is to provide 5 a permanent hair waving apparatus in which a single heating element produces substantially the same results which have previously been obtained by permanent hair waving apparatus which are provided with 10 two or more heating elements.

Another object of this invention is to construct a heating device provided with pockets for retaining the vapors used in treating the hair during the waving process.

15 A further object of this invention is to construct a permanent hair waving apparatus, the various parts of which can be stamped from sheet metal.

The invention possesses other advantageous 20 features, some of which with the foregoing, will be set forth at length in the following description, where I shall outline in full that form of the invention which I have selected for illustration in the drawings accompanying and forming part of the present specification. In said drawings I have shown one form of permanent hair waving apparatus embodying the improvements of my invention, but it is to be understood that I do not 25 limit myself to such form, since the invention, as set forth in the claims, may be embodied in a plurality of forms.

In the drawings:

Figure 1 is a perspective view of my apparatus in its operative position.

Figure 2 is an end elevation with the arm of one of the clamping members shown partly in section.

Figure 3 is a sectional view taken on the 40 line 3—3 of Figure 2 looking in the direction as indicated by the arrows.

Figure 4 is a perspective view of one of the clamping members.

Figure 5 is a perspective view of the other 45 clamping member to which a heating element and terminal block have been attached.

Figure 6 is a cross sectional view of the heating element per se.

The improvements of my invention relate 50 to permanent hair waving apparatus such as are now in common use. In the construction of such apparatus it is customary to employ two spring pressed pivoted semi-cylindrical clamping members. Each of the 55 clamping members is provided with a heat-

ing element, both of which are of a semi-cylindrical form and each of which is nested within one of the clamping members. In the use of these devices the hair to be waved is wrapped about a mandrel after first being 60 washed in certain chemical solutions. A layer of flannel or other suitable material is then wrapped about the hair, a layer of metal gauze is wrapped about the flannel and over this is placed a clamping member 65 such as above described. I propose to construct a device in which a single heating element is so positioned with respect to both of the clamping members, that heat will be readily conducted from it to both of the 70 clamping members and so serve the same purpose and produce the same results which have previously been accomplished by the use of two heating elements. I further propose to get a more even distribution of heat 75 by providing the shell or jacket, in which the heating element per se is carried, with apertures. These apertures also serve as pockets in which the vapors produced by the chemicals in which the hair has been washed 80 may be retained. Although the vapors so used form no part of the present invention, it may be well to state that such vapors play an important part in permanently waving the hair, and that therefore the provision 85 of these pockets for holding such vapors is an important improvement of my invention.

The form of both the clamping members and the shell or jackets which enclose the heating element per se is such that they can be 90 readily stamped from a piece of sheet metal. The heating element together with the shell or jacket is so constructed as to be readily detachable whenever desired.

In the embodiment of my improvements 95 shown herein two T-shaped members generally designated as A and B, and best shown in Figures 4 and 5, are stamped from a sheet of aluminum or other suitable metal. As shown in Figures 1, 2, 4 and 5 these T- 100 shaped members have been shown as inverted. Midway between the arms 1 and 2 of the T-shaped members A and B are lugs 4, 5, 6 and 7. These lugs as shown in the various figures are struck up at right 105 angles to the arm members 1 and 2 and are provided with apertures 31 through which a pin 3 is placed to pivotally secure the members A and B. A spring 10 is coiled about the pin 3 and has one of its ends pressing 110

against the arm 1 while the other end is pressed against the arm 2 and so serves to urge the cross bars or clamping members 8 and 9 to a closed position. The clamping members 8 and 9 have been bent into a semi-cylindrical form as shown in Figures 1, 2, 4 and 5, and are provided at their outer edges with fiber strips 41 and 42, which prevent the hot edges of the clamping members from coming into direct contact with the flannel covering. These strips are secured to the clamping members 8 and 9 by means of rivets 43.

A heating element of semi-cylindrical form generally designated as 12 is made up of a mica core 35 about which a resistance wire 36 is wound and which is entirely insulated by mica strips 37. Metallic semi-cylindrical members 38, cover both the exterior and interior surfaces of this construction and all this is then socketed or enclosed in a shell 11. This shell 11 is made from a rectangularly stamped sheet of metal which has been bent into a semi-cylindrical form and whose outer edges 32 have been bent back upon themselves as shown in Figure 6, to lock the heating element in place. The ends of the shell 11 have been struck up to close the ends of the heating element as a best shown at 33 in Figure 5, and the edges of the shell member are rounded off so as to prevent any sharp kinks from being formed in the permanent wave. The inner surface of the shell 11 is apertured as at 13 to permit of a more even distribution of heat within the cylindrical member formed by the clamping members 8 and 9 and by the shell 11. These apertures also serve as vapor pockets.

The shell 11 together with the heating element 12 is concentrically disposed within and secured to the clamping member 9 by means of a screw 14 which is engaged by a nut 15 in engagement with the outer surface of the clamping member 9. As best shown in Figures 2 and 5, the upper left half of the shell 11 extends beyond the clamping member 9. This permits the upper half of the clamping member 8 to overlap this exposed outer surface of the shell 11. By such a construction it will be seen that a substantial part of the cylindrical surface of the shell 11 is engaged by both the clamping members 8 and 9. Since all the elements so far described are metallic with the exception of the insulation which customarily surrounds the heating element 12, it will be readily seen that heat is readily conducted from the shell 11, not only to the clamping member 9, but also directly to the clamping member 8.

A terminal block 16 is secured to the outer lower end of the arm 2 by means of a screw 17 which engages the nut 18 on the inner surface of the member 2. The leads to the

heating element 12 are secured within this terminal block to the customary contact or socket members. A cord 40 carrying a plug 19 is in turn secured to these contact members. The ends 39 of the resistance wire which go to make up the heating element 12 are threaded through apertures 34 in the heating element and are led through openings 20 and 21 as shown in Figure 1 into the contact members of the terminal block 16. The leads from the resistance or heating elements are kept out of contact with the clamping member 9 due to the fact that these leads are held in spaced relation by the terminal block 16.

By the disposition of the heating element with respect to the clamping members 8 and 9 as above described, it will be seen that due to the fact that the heating element is in contact with both of the clamping members, conduction between these elements is obtained. By such a construction one of the usual heating elements can be done away with and the cost of manufacturing these devices is thereby considerably decreased.

The apertures in the shell surrounding the heating element serve to enclose the vapors which are beneficial to the waving process and also permit of a more even distribution of heat.

The fiber strips prevent the flannel covering over the hair from being excessively heated. It will be noted that the metallic gauze which is placed about the flannel covering serves a similar purpose within the clamping members.

The entire construction may be stamped from sheet metal, thus making an efficient economical device.

I claim:

1. Permanent hair waving apparatus comprising two hinged semi-cylindrical clamping members, a single semi-cylindrical heating element carried by one of said clamping members and overlapped by the other of said clamping members when said clamping members are in their closed position.

2. Permanent hair waving apparatus comprising two hinged semi-cylindrical clamping members, a semi-cylindrical heating element carried by one of said elements and so disposed that a substantial part of its outer surface is in contact with the other of said clamping elements when said elements are in their closed position.

3. A permanent hair waving apparatus comprising two hinged semi-cylindrical clamping members and a semi-cylindrical heating element carried by one of said clamping members in heat conducting relation with both clamping members.

4. A permanent hair waving apparatus comprising two hinged semi-cylindrical clamping members, a semi-cylindrical aper-

tered shell nested within both of said clamping members and a quickly detachable heating element arranged within said shell.

5. A permanent hair waving apparatus comprising two spring pressed pivoted arms, semi-cylindrical clamping members carried at corresponding ends of each arm, a semi-cylindrical apertured shell concentrically disposed within said clamping members 10 having half of its outer surface always in contact with one of said clamping members and its other half in contact with the other of said clamping members when said clamping members are in their closed position, and 15 a heating element carried within said shell.

6. A permanent hair waving apparatus comprising two pivoted clamping members and a heating element whose outer surface is substantially equally overlapped by and 20 in contact with both of said clamping members, carried by one of said clamping members.

7. A permanent hair waving apparatus comprising two hinged semi-cylindrical

clamping members, a semi-cylindrical heating element carried by one of said clamping members in heat conducting relation with both clamping members and fiber strips carried by and protruding beyond the outer edges of the clamping members.

8. A permanent hair waving apparatus comprising two spring pressed pivoted arms, semi-cylindrical clamping members carried at corresponding ends of each arm and provided at their outer edges with protruding strips of insulating material, a semi-cylindrical apertured shell concentrically disposed within said clamping members having half of its outer surface always in contact with one of said clamping members and 40 its other half in contact with the other of said clamping members when said clamping members are in their closed position, and a heating element within said shell.

In testimony whereof I have hereunto set 45 my hand.

ANTON T. WEHNER.
